ATTORNEY

UNITED STATES PATENT OFFICE.

JOSEPH W. STORM, OF COSHOCOTON, OHIO.

PITMAN.

1,242,492.

Specification of Letters Patent.

Patented Oct. 9, 1917.

Application filed October 11, 1916. Serial No. 125,066.

To all whom it may concern:

Be it known that I, JOSEPH W. STORM, a citizen of the United States, residing at Coshocton, in the county of Coshocton and State of Ohio, have invented certain new and useful Improvements in Pitmen, of which the following is a specification.

This invention relates to an improved pitman and the principal object of the invention is to provide improved means for connecting the pitman with the driving disk which will of course be rotatably mounted and to further provide improved means for lubricating the pitman.

Another object of the invention is to provide an improved type of bushing fitting within the pitman head and about the pivot pin for the pitman, the bushing being so constructed that it will be held against rotary movement within the pitman head.

Another object of the invention is to provide an improved type of securing means for the nuts holding the pitman upon the pivot pin or stub shaft, the locking means being so mounted that it may be releasably held in an inoperative position.

Another object of the invention is to so construct the stub shaft that it may be releasably connected with the driving disk.

This invention is illustrated in the accompanying drawings, wherein:

Figure 1 is a view in elevation showing a fragment of the driving disk and one end portion of the pitman connected therewith.

Fig. 2 is a sectional view taken along the line 2-2 of Fig. 1, with the stub shaft shown partially in elevation.

Fig. 3 is a sectional view through one end of the pitman taken along the line 3-3 of Fig. 2.

Fig. 4 is a fragmentary sectional view taken along the line 4-4 of Fig. 3, one portion of the stub shaft being shown in plan.

The driving disk 10, a fragment of which is shown will be rotated in any suitable manner and is provided with a threaded opening 11 in which the threaded inner end portion 12 of the stub shaft 13 is screwed and securely held in place by means of the set screw 14. This stub shaft is tapered longitudinally and terminates in a threaded outer end portion 15 having longitudinally extending grooves 16 formed therein. From an inspection of Fig. 2 it will be readily seen that when the stub shaft becomes worn, the set screw 14 can be loosened and

the stub shaft then removed from the driving disk and a new stub shaft put in place.

The pitman 17 is provided with a head 18 having a passage 19 formed therein to receive the stub shaft 13, a bushing 20 being placed in the passage 19 and held against rotation therein by means of the lugs 21 fitting into side sockets leading from the passage 19. This bushing may be formed of any suitable material and is provided with bottom openings 22 and side openings 23 through which lubricating oil may pass to lubricate the stub shaft and permit the stub shaft to turn easily in the bushing. A spacing washer 24 is provided to hold the head of the pitman in spaced relation to the driving disk 10 and thus permit the pitman to move freely. A pocket 25 is formed in the pitman head about the bottom and side portions thereof as shown in Fig. 3 and is provided with an inlet neck 26 to permit lubricant to be poured into the pocket. It will thus be seen that as the pitman moves longitudinally and the stub shaft rotates in the bushing, the lubricant in the pocket will feed through the openings 22 and 23 to lubricate the stub shaft.

When in use, the stub shaft is screwed into the threaded opening 11 of the driving disk and the pitman is then placed upon the stub shaft and engages the spacing washer previously placed upon the stub shaft. The securing nut 27 is then screwed upon the threaded outer end portion of the stub shaft, the locking pin 28 being drawn outwardly by means of the ring 29 and then turned so that the ring will rest upon the strips 30 to hold the locking pin in the inoperative position. After the nut has been tightened the desired amount, the pin will be again turned to the position shown in full lines and the ring will pass between the strips 30 thus permitting the head 31 to fit into one of the grooves 16. Of course, it is understood that as many grooves 16 as desired may be provided. The spring 32 releasably holds the locking pin in the operative position and therefore the nut will be securely but releasably held in place and prevented from working loose as the pitman moves. As previously explained, the lubricant will be poured into the pocket and the stub shaft will be lubricated from the bottom and side portions instead of from the top as is usually the case thus preventing waste of the lubricant.

What is claimed is:—

A device of the character described comprising a driving element, a stub shaft extending from said driving element, a pitman 5 provided with a transversely extending passage through which said stub shaft extends to rotatably mount the pitman and with side pockets leading from the passage, a bushing in the passage of the pitman 10 having side lugs fitting into the pockets to prevent rotation of the bushing, the bottom portion and one side portion of the bushing being provided with lubricant passages, the pitman being provided with a lubricant 15 pocket extending longitudinally of the perforated portion of said bushing, a disk upon the shaft holding the pitman in spaced relation to the driving element and engaging the bushing to hold the bushing in the pitman, and means for holding the pitman 20 upon the stub shaft.

In testimony whereof I affix my signature in presence of two witnesses.

JOSEPH W. STORM.
